UNITED STATES PATENT OFFICE

2,535,949

MANDREL POSITIONING DEVICE FOR TUBE MILLS AND THE LIKE

John W. Offutt, Ellwood City, Pa., assignor to
National Tube Company, a corporation of New Jersey

Application January 11, 1945, Serial No. 572,283

3 Claims. (Cl. 80—13)

1

This invention relates to pipe or tube mills employing a rotatable mandrel bar, and more particularly to improvements in the mandrel positioning devices used therein.

In rolling seamless pipe or tubing in conventional mills, a mandrel plug is held between the metal working rolls by a mandrel bar. Since the workpiece is telescoped over the mandrel bar during the rolling operation, it is necessary to withdraw the mandrel bar from the metal working position in order to remove the workpiece therefrom. Means are provided to rapidly withdraw the mandrel bar and to reposition it after the workpiece is removed.

In addition to the foregoing mandrel movement, it is necessary to provide a longitudinal adjustment of the mandrel bar to position accurately the mandrel plug between the metal working rolls. Heretofore, such adjustment has been effected by an adjusting nut combined with the thrust bearing assembly, to which the rear end of the mandrel bar is attached. Rotation of this nut moves the thrust bearing within its housing and the attached mandrel bar relative to the stationary latch housing of the mill to thereby position the mandrel bar and plug relative to the metal working rolls.

It is accordingly an object of this invention to provide a seamless tube mill mandrel bar adjustment which permits the use of a thrust bearing of more substantial construction than is possible in conventional designs.

It is a further object to provide an adjustment for mandrel bars which is rugged and simple in design and adapted to conventional tube mills.

The foregoing and further objects will be apparent from the specification and drawings, wherein:

Figure 1 is a plan view of a seamless pipe or tube mill embodying my improved mandrel adjustment device;

Figure 2 is an enlarged plan view of the mandrel bar carriage and the associated adjusting members;

Figure 3 is an enlarged sectional elevation of the same taken on line III—III of Figure 2; and

Figure 4 is a cross section on line IV—IV of Figure 3.

Referring more particularly to the drawings, the numeral 2 designates a pair of metal working rolls between which a mandrel plug 5 is held in metal working position by a mandrel bar 4.

After a tubular workpiece A has been completely rolled between the metal working rolls 2 and over the intermediately disposed mandrel plug

5, and has been telescoped thereby over the mandrel bar 4, it is removed from the mill by withdrawing the mandrel bar and moving the workpiece to an adjacent skidway 6 by conventional kick-off arms (not shown). In accordance with conventional design, the mandrel bar 4 is carried by a carriage 15 which reciprocates on an elongated frame or slideway 9 forming part of the outlet bed of the mill.

The outlet bed is also provided with a pair of suitably spaced sheaves 10, one of which is driven by a reversible motor (not shown). A cable 12 connects the sheaves for conjoint rotation and the ends thereof are attached to the mandrel bar carriage 15. Thus by operating the reversible motor (not shown), the mandrel bar carriage 15 and the attached mandrel bar 4, are moved toward or away from the mill for the purposes above described.

A housing 20 is vertically disposed on either side of the outlet bed of the mill adjacent the mandrel bar carriage 15 when it is in its forward or metal rolling position and extends thereabove as shown in Figures 2 and 3. A shaft 22 is journaled in the latch housing 20 transversely thereof and embodies a pair of latch members 23 adjacent the latch housing 20.

A trunnion mounted, fluid actuated cylinder 25 is carried by the housing 20 at one side and rearwardly of the shaft 22 and somewhat elevated thereabove. The exposed end of the piston is pivotally connected as at 26 to a crank arm 27 keyed or otherwise secured to the shaft 22. Thus it is seen that energization of the fluid actuated cylinder 25 will partially rotate the shaft 22 so as to raise the latch members 23 out of engagement or lower them into engagement with suitable abutment plates on a thrust bearing saddle, hereinafter described.

The mandrel bar carriage 15 comprises a thrust bearing housing 30 having a thrust bearing 31 positioned and held therein by nuts 32. An upwardly projecting box-like lug 35 is integrally mounted on top of the bearing housing 30 and is provided with recesses 36 in the forward and rearward faces thereof. The housing 30 is also provided with outwardly extending integral side flanges 40 having upturned ends 41 forming slideways 42 on the upper surfaces of the flanges. The lower sides of the projections 40 are adapted to engage the lower ways 9 of the outlet bed of the mill.

Reciprocably mounted on the ways 42 of the housing 30 is a saddle 45 which has upwardly extending interiorly threaded lugs 46, at either

end thereof, which are in axial alignment with the recesses 36 in the lug 35. Disposed in the lugs 46 are adjusting screws 48, the inner ends of which are received in the recesses 36 in the lug 35 and thereby lock the saddle 45 in position.

A pair of recesses 50 is provided on the upper surface of the side members of the saddle 45 intermediate the ends thereof and the forward sides of the recesses are provided with angularly disposed bearing plates 52. The angularity of the plates 52 and the lower ends of latch members 23 is such that axial thrust applied to the bearing 31 during rolling operations is transmitted through the housing 38, adjusting screws 48 and saddle 45, holds the housing 38 and the saddle 45 rigidly together, and also holds the housing 38 firmly on the slideways 9.

In operation, the reversible motor (not shown) is operated to position the plug 5 intermediate the rolls 2. Cylinder 25 is then activated to lower the latch 23 so that it engages the plates 52 on the saddle 45. This prevents rearward axial movement of the plug 5 and bar 4. Accurate adjustment of the plug 5 between the rolls 2 is then effected by turning the screws 48. After a workpiece A has been rolled and telescoped over the mandrel bar 4, the mandrel bar is retracted to remove it from the workpiece A by operating the cylinder 25 to lift the latch 23. The reversible motor (not shown) is then energized to move the mandrel carriage 15 away from the mill. As soon as the workpiece has been removed, the foregoing operations are repeated to reposition the plug intermediate the rolls and to remove telescoped workpieces from the mandrel bar. However, it is not necessary to readjust the plug 5 by turning the screws 48 for each workpiece since this may need only be done from time to time as it becomes necessary.

While I have shown and described one specific embodiment of my invention, it will be understood that this embodiment is merely for the purpose of illustration and description and that various other forms may be devised within the scope of my invention, as defined in the appended claims.

I claim:

1. In a seamless pipe or tube mill having a reciprocable mandrel bar and an outlet bed including slideways for reciprocating said mandrel bar, a thrust bearing housing supporting said mandrel bar, oppositely disposed longitudinally

extending flanges on said housing, the lower surfaces of said flanges adapted to slide on said slideways and the upper surfaces thereof forming secondary slideways, an adjustable saddle mounted on said housing and adapted to ride on said secondary slideways and retractable means engaging said saddle to hold said mandrel bar against longitudinal thrust.

2. In a seamless pipe or tube mill having a reciprocable mandrel bar and an outlet bed including slideways for reciprocating said mandrel bar, a thrust bearing housing supporting said mandrel bar, oppositely disposed longitudinally extending flanges on said housing, the lower surfaces thereof adapted to slide on said slideways and the upper surfaces thereof forming secondary slideways, an upwardly extending lug on said housing, a saddle adapted to ride on said secondary slideways, at least one adjusting screw engaging said saddle and said lug to position said saddle with respect to said housing and retractable means engaging said saddle to hold said mandrel bar against longitudinal thrust.

3. In a seamless pipe or tube mill having a reciprocable mandrel bar and an outlet bed including slideways for reciprocating the mandrel bar, a thrust bearing housing supporting said mandrel bar, a pair of oppositely disposed vertically spaced slideways on said housing, the lower of said slideways adapted to ride on the first mentioned slideways forming part of the outlet bed of the mill, an adjustable saddle mounted on said housing and adapted to ride on the upper of said pair of slideways and a retractable latch adapted to engage said saddle to hold said mandrel bar against longitudinal thrust and to be disengaged therefrom to permit said mandrel bar to be reciprocated.

JOHN W. OFFUTT.
